DESIGN FOR A LAMP BASE

Roger Q. Peck, Hawthorne, Calif.

Application December 14, 1945, Serial No. 124,752

Term of patent 3½ years

(Cl. D48—20)

To all whom it may concern:

Be it known that I, Roger Q. Peck, a citizen of the United States and resident of the city of Hawthorne, county of Los Angeles, State of California, have invented a new, original, and ornamental Design for a Lamp Base, of which the following is a specification, reference being had to the accompanying drawings, forming a part thereof, in which:

Fig. 1 is a perspective of a lamp base, showing my new design;

Fig. 2 is a side elevation;

Fig. 3 is a top plan view; and

Fig. 4 is a bottom plan view thereof.

I claim:

The ornamental design for a lamp base, substantially as shown.

ROGER Q. PECK.
